United States Patent Office.

JAMES A. WOODBURY, OF BOSTON, MASSACHUSETTS.

Letters Patent No. 63,351, dated March 26, 1867.

IMPROVEMENT IN VALVES FOR STEAM ENGINES.

The Schedule referred to in these Letters Patent and making part of the same.

TO ALL WHOM IT MAY CONCERN:

Be it known that I, JAMES A. WOODBURY, of Boston, in the county of Suffolk, and State of Massachusetts, have invented certain new and useful Improvements in Arranging and Operating the Valves of Steam Engines, to effect a variable cut-off operated from the regulator, and that the following is a full, clear, and exact description of the same, reference being had to the accompanying drawings, making a part of this specification, in which—

Figure 1 represents an external view of one side of the steam cylinder and of the steam chests.

Figure 2 represents a section through the same, taken at the red line xx of fig. 1.

Figure 3 represents an end view of the cylinder and of the steam chests.

Figure 4 represents a cross-section through the steam cylinder and chests, taken at the red line yy of fig. 1.

Figure 5 represents a view of the exhaust ports, and shown as detached from the steam cylinder.

Figure 6 represents different views of the valves, also detached from their places.

Similar letters of reference where they occur in the several figures denote like parts in all the drawings.

My invention consists in a valve so constructed and arranged in reference to the openings in the walled ports upon which it works as to enable me to regulate the movement of the induction valves, so as to cut off the steam at any desired part of the stroke of the piston, without reference to the exhaust valves.

This arrangement of valves is especially adapted for a variable cut-off. The cam shown in the drawings has a fixed throw, and would move the valves a uniform distance at all times, but with a movement varied in speed. But I propose to use any of the common and well-known forms of variable or shifting cams, so as to get a variable cut-off from the regulator or governor, and one that will vary the throw as well as the time in making it. The valves are balanced, or nearly so, and as such especially adapted to a variable cut-off, as they can be used or moved with so little power that the governor will regulate the engine in the most accurate manner. The less motion the valve has, provided it is sufficient to open the ports for the inlet of the steam, the more sensitive or quick will be the action of the governor, and the nearer perfect will be the action or regulation of the engine. This motion and action I attain by having two or more ports upon each side of the walls, which are so constructed as to let the steam into all the ports at once by means of slants or inclines in the outside of the valves and a suitable opening in the centre and through the top of the valve.

To enable others skilled in the art to make and use my invention, I will proceed to describe the same with reference to the drawings.

A represents a steam cylinder, having the inlet chests and valves and valve ports, B, arranged upon its side, and the exhaust passages, ports, and valves C underneath. D is a cam-shaft, which may be revolved from any part of the engine, and has upon it a cam, a, which as it revolves strikes alternately the valve-rods b b' which are attached to the inlet valves e e' and open them, said valves being closed by a spring, d, (one for each valve, but one only being shown in the drawings,) after the cam leaves the rods respectively. When the ordinary shifting or changeable cam is used, then I would propose to put it on the governor shaft, and work it by the governor. e e' are the exhaust ports or valves, communicating with the exhaust passage E and exhaust-pipe F. The exhaust valves are operated from the main shaft by means of the rods f f'. There are three openings or ports, 1 2 3, shown in the walls, which ports are controlled by the inlet and exhaust valves. These may be reduced to two, or be more than three, as may be found expedient; I prefer three as acting well in practice. The steam in the inlet passes through an opening, i, in the top of the valve as well as through openings at both of its ends, g g. There are two sets of walled ports, h h, with three openings in each side of each wall, said walls having a division, n, in them, so that there are twelve openings or ports altogether, which are covered, exposed, or controlled by each valve, e e', which make an immense amount of steam way by a very slight movement of the valve.

Having thus described the operation of my steam valve, what I claim, and desire to secure by Letters Patent, is—

The valve, constructed as described, and arranged with reference to the openings in the walled ports upon which it works, substantially as described, which arrangement enables me to regulate the movement of the induction valves so as to cut off the steam at any desired part of the stroke of the piston without reference to the exhaust valves.

JAMES A. WOODBURY.
